VENTILATORS FOR WATER CLOSETS,
KITCHENS AND THE LIKE
William L. Martz, 20980 Canyon View Drive,
Saratoga, Calif.
Filed Aug. 1, 1963, Ser. No. 300,414
4 Claims. (Cl. 4—218)

The present invention relates to ventilators for water closets and is adapted for use in combination with the water closet system including a conventional tank.

This application is a continuation-in-part of my application Serial No. 279,689, filed March 22, 1963, now abandoned.

An object of this invention is to provide an improved 15 ventilating arrangement which may be used in conjunction with an existing ventilating blower for exhausting undesired kitchen odors such as are given off in the preparation of food such as onions.

Another object of this invention is to provide an improved arrangement for efficiently eliminating the obnoxious odors that appear in a closet bowl during use, and it is particularly adapted for use in connection with conventional water closet equipment.

Briefly, this invention provides facilities for exhausting the odors from the water closet bowl by an air exhauster or blower positioned in the attic or on the building roof. The exhauster or blower is connected to the space above the water level in the water closet tank or to the top of the overflow pipe in said tank by a plastic pipe which preferably extends down from the attic between wall members so that it may be led to the water closet tank through a suitable hole cut in the wall behind the tank, and the lower end of this plastic pipe is positioned above the normal water level in the tank. When a motor driven blower is used a suitable switch for controlling the exhaust blower is provided in the bathroom wall, and this switch may be adjacent to the normal bathroom light switch or it may be made to be operated simultaneously with the light switch if desired.

In accordance with this invention, the existing exhaust blowers that are provided in the ceiling of the bathroom and in the ceiling of the kitchen are each equipped with a suitable suction nozzle. A plastic pipe is provided in each case with the upper end thereof connected to the nozzle. In the bathroom fixture the lower end of the plastic pipe is positioned in the tank of the water closet. In the kitchen fixture the lower end of the plastic pipe opens under a small hood provided over or adjacent to the kitchen sink. Thus in each case the undesired odors are sucked up through the plastic pipe by the negative pressure generated under the exhaust blower. This apparatus may be installed as an attachment to the kitchen and bathroom exhaust blowers if desired.

Other features and objects of this invention will be apparent to those skilled in the art to which it relates from the following specification, claims and drawing in which, briefly:

FIG. 1 is a vertical sectional view taken through a bathroom equipped with this invention;

FIG. 2 is a view of the water closet tank partially broken away to show the inside mechanism thereof;

FIG. 3 is a sectional view taken along the line 3—3 of FIG. 2;

FIG. 4 is a sectional view taken along the line 4—4 of FIG. 3;

FIG. 5 is a detail view of a modified form of this invention adapted to be used with the flush type valves;

FIG. 6 is a view taken along the line 6—6 of FIG. 5;

FIG. 7 is a vertical sectional view taken through a bathroom equipped with another form of this invention;

2

FIG. 8 is a sectional view taken along the line 8—8 of FIG. 7 showing how the plastic pipe passes through the gasket provided under the cover of the water closet tank;

5 FIG. 9 is a vertical sectional view taken through a kitchen equipped with an exhaust hood positioned above the kitchen sink whereby undesired odors given off by food such as onions may be exhausted during the preparation of such food;

FIG. 10 is a vertical sectional view taken through a bathroom equipped with still another form of this invention;

FIG. 11 is a sectional view taken along the line 11—11 of FIG. 10; and

FIG. 12 is a fragmentary view of a ventilator unit made in accordance with this invention equipped with a heat exchanging unit.

Referring to the drawing in detail, there is illustrated a water closet ventilator which is adapted to be used with the conventional water closet equipment employing a bowl 10 connected by means of the pipe 11 to the water tank 12. The tank 12 is of generally conventional construction and is provided with a bulb valve 14 that is seated on the member 13 to which the pipe 11 leading to the bowl 10 is connected and to which the overflow pipe 15 is also connected.

The top end part of the overflow pipe 15 is coupled to the lower end of the plastic tubing 16 which is stretched over the pipe 15 so as to make a snug connection therewith. The pipe or tubing 16 may of course be made of copper or other material beside plastic if desired. The pipe 16 passes out of the tank and through a suitable hole 20a formed in the wall 20 so that it passes between the wall members 20 and 21 up into the attic of the building where it is connected to the fan housing of the electric motor driven exhaust fan 17. The top portion of the fan housing is provided with a pipe 18 leading out of the building through a suitable hole formed in the roof. Electric current to the electric fan 17 is controlled by 40 means of the switch 19 which may be positioned adjacent to the door of the bathroom. Also the bathroom light may be controlled by this same switch, if desired so that both the motor of the fan 17 and the lights may be energized simultaneously.

45 The part of the pipe or tubing 16 passing over the top edge of the tank 12 may be flattened to assume the configuration shown in the part 16a in FIGS. 3 and 4 so that this part of the tube fits under the cover of the tank more readily. Where desired the top of the tank 12 may 50 be cut away slightly by using a conventional diamond impregnated saw so as to provide a suitable notch or recess for receiving the tube 16. In case such a notch or recess is provided to the upper edge of the tank, then the tube 16 need not be flattened.

55 The tank 12 is also provided with conventional equipment such as the inlet supply pipe 22 which furnishes water supply to fill the tank to the predetermined level. This inlet pipe 22 is connected to the valve 23 which is also of conventional construction and which is controlled 60 by means of the bulb 24 that is mounted on one of the rods 25, the other end of this rod being connected to the valve control linkage 26. An external lever 27 is provided on the tank 12 and this lever which is connected by means of the members 28 to the bulb valve 14 is used for lifting this bulb valve when it is desired to flush the toilet. A bowl refilling pipe 29 is also connected between the valve 23 and the top part of the overflow pipe 15.

65 The upper end of the overflow pipe 15 is provided with a small hollow elbow 30 one end of which is attached thereto and the other end or upper part of which provides a seat for the ball shaped float valve 32. The upper

part of the elbow 30 forms an inlet to the overflow pipe 15 which is controlled by the float valve 32. The float valve 32 is hollow and is adapted to float on the water if the water level in the tank reaches above the seating surface of the elbow 30. Thus this valve opens and allows the excess water to flow into the overflow pipe 15. A suitable screen 31 is provided for enclosing the ball 32 to prevent this ball from escaping the immediate vicinity of the seat on the elbow 30. Thus the screen 31 is large enough to permit the bulb 32 to leave its seat but it functions to guide the ball to said seat when the water level is lowered.

This invention provides an electrically actuated exhaust system for removing odors from the closet bowl and directing them to the vent stack 18 opening to the outer atmosphere on the roof of the building. Thus the person using the bathroom turns on the fan 17 by manipulating the wall switch 19 which, as previously described, may also be used for turning on the light on the bathroom. The exhaust fan 17 draws the air from the closet bowl 10 through the pipe 11, the overflow pipe 15, pipe 16 and forces it out through the stack 18. This exhausting operation continues as long as the fan 17 is turned on.

In FIG. 5 there is illustrated a modified form of this invention that is adapted to be used with toilet bowls equipped with a flush type valve, also sometimes referred to as a Sloan valve. The toilet bowl 10 which is of conventional construction is provided with a pipe 33 which connects to the flush valve 39. This flush valve is connected to a water supply pipe and it is also provided with a trip lever 40 which is manually tripped when it is desired to flush the toilet. The pipe 33 is provided with a connection 34 which extends through the bathroom wall 29 and connects to the pipe or tubing 16b that corresponds to the pipe 16 shown in FIG. 1. This pipe leads to the attic exhaust fan 17 and to the vent pipe 18 so that when the fan is turned on air is drawn out of the bowl 10 through pipe 33, pipe 34 and pipe 16b.

The pipe 33 is also provided with a butterfly type flap valve which includes the flap 35 that is normally held in horizontal position with respect to its pivot 36. A weight 37 that is connected to the flap 35 is provided for this purpose. However, when the flush valve 39 is tripped by manual operation of the handle 40, so that water runs therethrough into the pipe 33 the water engages the flap 35 and forces it against the seat 38 thereby closing the passage into the pipe 34 during the flushing of the toilet bowl 10. The pivot 36 may be made of two opposing Allen type set screws having pointed pivot surfaces engaging the shaft 36a of the flap valve. Also the seat 38 extends substantially around the mouth of the pipe 34 and may consist of a neoprene member cemented around said mouth.

Thus the pipes 33 and 34 form a T connection between the valve 39, the bowl 10 and the pipe 16b which may be of plastic. The portion 34 thereof extends into the wall structure where it is connected to the pipe 16b which may be stretched thereover to make a snug fit. The valve 39 is connected to a water supply pipe in a conventional manner.

The form of this invention shown in FIGS. 5 and 6, used with flush type valves which are also sometimes referred to as Sloan valves, also functions to prevent a back flow since the flap valve 35 when in the position shown in FIG. 5 will prevent back flow into the valve 39 from the pipe 33. This valve will then serve a dual purpose, that is, vent valve plus back flow preventer.

Another form of this invention is shown in FIGS. 7 and 8. A conventional exhaust blower including the fan member 41 and motor 42 for driving same is positioned in the housing 43 which has an inlet 44 opening into the bathroom so that the air from the bathroom may be exhausted outward through the stack 46 which is positioned on the roof of the building. This blower arrangement is provided with a nozzle 47 which has an elongated opening

that is positioned directly under one side of the fan so that when the fan is driven a negative pressure is created in this nozzle and gases are sucked up through the plastic pipe 48 from the toilet bowl 51.

5 The lower opening 50 of the plastic pipe is positioned inside of the water closet tank 49 and this opening is positioned above the normal water level in this tank. A suitable gasket 53 of resilient material such as foam rubber, plastic or the like, is provided under the cover 52 and this gasket seals the cover to the top of the tank. 10 Thus the suction through the plastic pipe 48 functions to exhaust the air from the space above the water level in the top of the tank and at the same time the gases from the toilet bowl 51 are sucked up through the overflow pipe 15 that is positioned in the tank 49. This overflow pipe is similar to the pipe 15 shown in FIGS. 1, 2 and 3. 15 However, the inlet 50 of the plastic pipe is not connected directly to the top of this overflow pipe since this is not necessary inasmuch as the gasket 53 provided between the cover 52 and the top of the tank 49 effectively seals the cover to the tank and prevents air leakage therebetween into the tank. Thus in this structure suction through the plastic pipe 48 draws the undesired gases through the overflow pipe from the toilet bowl 51.

20 The flattened part 54 of the plastic pipe 48 passes through the gasket 53 and the gasket may be cemented or otherwise jointed to this pipe at this point so as to make an effective seal therebetween.

The form of the invention shown in FIG. 7 may also be applied to a small kitchen ventilator, as shown in FIG. 9, in which the elongated nozzle 56 is attached to the conventional exhaust fan or blower 55. In this arrangement a small hood 58, which may be made of transparent plastic material, is provided above the kitchen sink 61 and the lower end 59 of the plastic pipe 57 opens under this hood 58 so as to provide suction under this hood whereby undesired odors produced in the preparation of food such as onions may be exhausted and prevented from spreading in the kitchen. The plastic pipes 48 and 57 are preferably positioned in the building walls between the studs or joists.

45 The embodiment of this invention illustrated in FIG. 10 is provided with an air exhauster unit 62 which is mounted on the top of the roof of the building and it is provided with a pipe that extends through a hole in the roof to connect to the upper end of the plastic pipe 48. This air exhauster 62 is of the type made by the G. C. Breidert Company of Pacoima, California which converts the action of winds from every direction into positive suction in the pipe 48. Inasmuch as this air exhauster 50 does not employ an electric motor this embodiment of this invention differs from that shown in FIG. 7 in that no electrically driven blower is required.

The lower end of the pipe 48 is open at 50 in the 55 tank 49 and it is positioned above the normal water level in this tank so that fumes from the bowl 51 may be drawn up into the tank 49 through the overflow pipe 49a and into the mouth 50 of the plastic pipe 48 through which said fumes are exhausted to the open atmosphere by 60 means of the air exhauster 62. A gasket 53 is provided between the top of the tank 49 and the cover 52 so that this cover is sealed to the tank. The pipe 48 is brought into the tank 49 through a gap in the gasket 53 and the gasket may be attached to the outside of the pipe.

65 The toilet bowl 51 is provided with a seat 51b and a cover 51a for the seat of conventional construction. Both the seat 51b and the cover 51a are hinged to the top of the bowl 51. The bottom side of the seat 51b is provided with a plurality of spaced rubber pads 51c which rest on the top of the toilet bowl 51 when the seat is down these pads are positioned on the top of the bowl as shown in FIGURE 11. Rubber or plastic sealing strips 51d are attached to the bottom of the seat by suitable glue or cement and these strips are positioned between the pads 51c as shown in FIG. 11 so that when

the seat is down on the bowl the air spaces between the pads 51c are sealed off, all around the top of the bowl except at the front thereof. Thus the air space between the front of the bowl and seat is open so that air may enter the bowl through this air space when the atmosphere from the inside of the bowl is drawn out through the overflow pipe 49a, and plastic pipe 48, sealing off the other air spaces by means of the plastic inserts 51d, prevents the undesired odors from leaving the bowl and entering the bathroom therethrough. The gases responsible for these undesirable odors are generally lighter than air and will be exhausted out through the pipe 48 and air from the bathroom will be sucked into the bowl either through the open space at the front of the bowl when the seat is occupied or covered or through spaces around the top of the seat that are not sealed off even when the seat is occupied. Because these gases are lighter than air, the strips 51d must be used to prevent these lighter gases from leaving the bowl into the bathroom before they are exhausted through pipes 49a and 48. The front air space between the bowl and the seat may be left open to permit air to enter the bowl from the bathroom therethrough as air and undesired gases are exhausted from the bowl through the pipes 49a and 48 and intermediate connections, while a person is sitting on the seat 51b. However, ordinarily sufficient air will enter the bowl through the hole in the top of the seat even when a person using the water closet bowl is sitting on said seat so that the space between the front pads 51c should also be sealed with a strip such as strip 51d.

In the forme of the invention shown in FIG. 12 the plastic pipe 48 is provided with a helical section 48a which is wrapped around the exhaust pipe 63. The exhaust or vent pipe 63 may be such as is provided to a water heater or the like and the helical coil 48a functions as heat exchanger between the pipe 63 and the pipe 48 to cause air to flow upward through the pipe 48. The helical coil 48a may be wrapped around a hot exhaust pipe from the heating system of the house if desired to produce this same result. In the summertime when the atmosphere in the attic of the house is generally quite hot, the arrangement using a coil such as the coil 48a may not be required since heating of the portion of the pipe 48 positioned in the attic is sufficient. In colder latitudes the heat exchanger coil 48a or a similar device may be used in conjunction with the air exauster 62 shown in FIG. 10 if necessary to provide the desired suction.

While I have shown preferred embodiments of the invention, it will be understood that the invention is capable of variations and modification from the form shown so that its scope should be limited only by the scope of the claims appended hereto.

What I claim is:

1. In a ventilator for a bathroom water closet which is provided with a water tank, a toilet bowl, a valve mechanism for flushing the water out of the tank into the toilet bowl, and an overflow pipe in the tank connected to the toilet bowl, the improvement comprising a ventilating pipe having the upper end thereof open to the atmosphere above the bathroom and the lower open end thereof positioned in the water tank above the normal water level

therein, means connected to the upper part of said ventilating pipe producing air flow upward through said ventilating pipe to draw air out of said water tank, said overflow pipe and said bowl, yieldable gasket means positioned between the upper edge of said water tank and the cover thereof, said ventilating pipe having a flattened portion at the bottom part thereof so that the width thereof does not exceed the thickness of said gasket means, said gasket means having a gap in the rear part thereof through which said flattened portion of said ventilating pipe is inserted into said tank, said toilet bowl having a seat and sealing means between said seat and said toilet bowl for substantially preventing fumes from escaping into the bathroom from said bowl while excrement is being voided into said bowl and said fumes and air are being exhausted from said bowl by said air flow producing means.

2. In a ventilator for a bathroom water closet which is provided with a water tank, a toilet bowl, a valve mechanism for flushing the water out of the tank into the toilet bowl, and an overflow pipe in the tank connected to the toilet bowl, the improvement as set forth in claim 1 further characterized in that the means connected to the upper part of said ventilating pipe to draw air out of said water tank comprises an air exhauster constructed to use wind from different directions to draw air up through said ventilating pipe.

3. In a ventilator for a bathroom water closet which is provided with a water tank, a toilet bowl, a valve mechanism for flushing the water out of the tank into the toilet bowl, and an overflow pipe in the tank connected to the toilet bowl, the improvement as set forth in claim 1 further characterized in that said ventilating pipe is made of plastic and the means connected to the upper part of said ventilating pipe producing air flow upward through said ventilating pipe comprises a section of said plastic pipe coiled around a heater vent pipe.

4. In a ventilator for a bathroom water closet which is provided with a water tank, a toilet bowl, a valve mechanism for flushing the water out of the tank into the toilet bowl, and an overflow pipe in the tank connected to the toilet bowl, the improvement as set forth in claim 1 further characterized in that the means connected to the upper part of said ventilating pipe producing air flow upward through said ventilating pipe comprises a nozzle positioned under the bathroom fan to draw air up through said pipe, said fan being mounted in a hole in the ceiling of the bathroom, said ventilator pipe including a pipe connected between said bathroom fan and the outer atmosphere.
